INTAGLIO PRINTING MACHINE

Joseph Barash, New York, N. Y.

Application December 7, 1936, Serial No. 114,588

3 Claims. (Cl. 101—157)

This invention relates to new and useful improvements in an intaglio printing machine.

The invention has for an object the construction of a device as mentioned which is characterized by a frame for guiding material between an intaglio printing roller and a pressure drum and supported in a manner so that it may be raised to an inoperative position, and the arrangement of an intaglio doctor blade located beneath the frame so as to be exposed and accessible when the frame is in the raised position.

Still further the invention proposes a specific arrangement for mounting and supporting the doctor blade so that it may be adjusted to various positions relative to the intaglio roller.

Another one of the objects of this invention is to construct the frame from side members connected by rods, and to provide guiding elements adjustably mounted upon the rods and adapted to be fixed in various positions to guide materials of different widths through the printing machine.

Other and important objects will become clear as the description of the invention proceeds.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a perspective view of an intaglio printing machine constructed according to this invention.

Fig. 2 is a plan view of Fig. 1.

Fig. 3 is a side elevational view looking in the direction of the line 3—3 of Fig. 2.

Fig. 4 is a fragmentary horizontal sectional view taken on the line 4—4 of Fig. 3.

Fig. 5 is a fragmentary enlarged sectional view taken on the line 5—5 of Fig. 3.

Fig. 6 is an elevational view looking in the direction of the line 6—6 of Fig. 2, a portion of this view being broken away to disclose interior parts.

Fig. 7 is a transverse sectional view taken on the line 7—7 of Fig. 6.

Fig. 8 is a fragmentary elevational view looking in the direction of the line 8—8 of Fig. 6.

Fig. 9 is a fragmentary horizontal sectional view taken on the line 9—9 of Fig. 3.

Fig. 10 is a fragmentary sectional view taken on the line 10—10 of Fig. 8.

Fig. 11 is a perspective schematic view showing

the intaglio printing roller and the pressure drum.

Fig. 12 is a perspective view of a portion of a piece of material printed by the machine.

Fig. 13 is a fragmentary sectional view taken on the line 13—13 of Fig. 12.

Fig. 14 is a plan view of two intaglio units shown in tandem for printing two colors.

The intaglio printing machine, according to this invention, includes a frame consisting of a base plate 10 supporting a pair of spaced parallel vertical wall plates 11. An intaglio printing roller 12 is rotatively mounted between the wall plates 11. A pressure drum 13 is superimposed on said intaglio roller and is adjustably mounted between the wall plates. A drive is provided for rotating the intaglio roller.

A pair of web elements 14 is formed on the inner faces of the wall plates 11 and are adapted to cooperate with a frame 15 for guiding material between the printing roller 12 and the pressure drum 13. A doctor blade 16 is arranged beneath the frame 15 and is cooperative with the intaglio printing roller 12 as hereinafter more fully described.

The intaglio printing roller 12 comprises a mandrel 17 on the central portion of which there is supported an engraved or cut intaglio printing sleeve 12a. Side sleeves 18 are mounted upon the mandrel 17 and serve to keep the printing element 12a in proper position on the mandrel. The pressure drum 13 is supported upon a shaft 20 which is rotative in bearings 21 vertically slidably supported on track elements 22 formed in the side walls 11. Pressure springs 23 are engaged on the top and bottom sides of the bearing blocks 21 and serve to resiliently support the pressure drum. A pressure control screw 24 is adjustably mounted on the top of each wall plate 11 and is cooperative with the pressure springs 23 for controlling the pressure of the pressure drum. These screws 24 may be turned down to increase the pressure or loosened to decrease the pressure.

The drive for the intaglio printing roller 12 includes a worm 25 fixed on an extended end of the mandrel 17 and located on the outer side of one of the wall plates 11. This worm 25 is in mesh with a worm pinion 26 on a drive shaft 27 rotatively supported in bearings 28 on the side of one wall plate. This drive shaft 27 is provided with a pulley 29 associated with a drive belt 30 adapted to engage with a prime mover, such as an electric motor. Rotations from the drive shaft 27 are

communicated to rotate the intaglio printing roller 12.

The webs 14 are cast or attached or in any other manner formed on the inner faces of the 5 vertical wall plates 11. These webs support the frame 15. The frame 15 comprises a pair of side arms 15^a which are pivotally supported at one of their ends on a spindle 15^b which is rotative through the wall plates 11. This spindle has a 10 projecting end which is provided with a handle 32 by which the frame may be lifted when desired. The side arms 15^a are provided with projecting stops 33 engageable with the ends of the webs 14 for limiting pivoting of the frame to a substantially vertical position, leaning slightly rearwards so as to maintain its position. Between the side arms 15^a there are a plurality of parallel rods 35. A pair of spaced guide elements 36 are slidably mounted on these rods. Each guide element 36 15 is provided with a projecting portion 37 equipped with a set screw 38 by which the element 36 may be held in a fixed position. The arrangement permits the guide elements 36 to be moved closer together or spaced apart to properly guide strips 20 of material of different widths through the printing machine.

The intaglio printing roller 12 is shown extending directly into an ink pan 40 which is supported on a bracket 41 supported on the base 30 plate 10. If desired, furnishing rollers, not illustrated on the drawings, may be interposed between the ink pan and the intaglio printing roll.

Another doctor blade 16' is provided at the rear end of the machine and is attached to a rotatable 35 rod 45^a.

The doctor blade 16 is fixedly mounted on a rod 45 and extends substantially radially thereof. This rod 45 is formed or provided with solid cylindrical heads 46 on the ends thereof. Each 40 of these heads is formed with a peripheral groove 46^a adapted to engage the material of the wall plates 11 to maintain the position of the rod 45. These heads 46 are slidably arranged in horizontal grooves or slots 48 formed in the wall plates 11. 45 One of the ends of each of the grooves 48 is provided with an enlarged portion 48^a through which the heads 46 may be moved when desired. This arrangement permits the rod 45 which supports the doctor blade to be removed from between 50 the wall plates 11 when desired.

Expansion springs 50 are arranged in the slots 48 and used between the braces of the slots and the heads 46 for normally urging the doctor blade support rod 45. This rod 45 is restrained 55 from moving outwards by adjustment screws 51 threadedly mounted on the wall plates 11. These screws 51 may be screwed inwards for moving the support rod 45 inwards and thus moving the doctor blade 16 correspondingly, or the screws 51 60 may be loosened to permit the springs 50 to move the doctor blade outwards. The doctor blade 16 and the support rod 45 are located beneath the frame 15 when the frame is in its lowered position.

65 An arrangement is provided for oscillating the doctor blade 16. This arrangement consists of a radial pin 53 projecting from an extended end 45' of the rod 45 and meshing with a slot 54^a in an arm 54 which is pivotally supported intermediate of its ends by a pin 55. The other end of the arm 54 is provided with a slot 54^b engaging an eccentric pin 56 mounted on a worm gear 57 meshing with a worm pinion 58 on an extending end 17' of the mandrel 17. The arrangement 70 75 is such that when the intaglio printing roller

rotates, the rotation will be transmitted to turn the gears 58 and 57 and to pivot the arm 54 and so oscillate the rod 45 and the doctor blade.

A radial arm 60 connects with the end 45' of the doctor blade support rod and supports an adjustable weight 61 which controls the pressure of the doctor blade engaging against the intaglio printing roller. In Fig. 12 a leather strip or other strip of material 63 is illustrated provided with an embossed design 64. This strip of material may be guided between the guiding elements 36 and over the frame 15 and through the printing machine which will apply color to the raised portions. This is merely by way of illustration. The intaglio printing machine may also print upon flat surfaces as well as the raised surfaces of embossed patterns.

The operation of the device is as follows:—

A web of material to be printed is supported upon the frame 15 between the guide elements 36 and is engaged between the intaglio printing roller and the pressure drum. Suitable pressure for printing is provided by the control screws 24. The doctor blade 16 will operate to scrape off excess ink from the intaglio printing roller so that the roller carries enough ink to print its engraved or cut design.

A feature of the printing machine is the frame 15 and the location of the doctor blade beneath the frame. Thus the frame 15 may be tilted upwards as indicated by the dot and dash lines in Figs. 3 and 7 to completely expose the doctor blade. The doctor blade may be removed by loosening the screws 51 until the heads 46 may pass through the large ends 48^a of the slots 48. It is an advantage to have the doctor blade located beneath the movable frame 15 in that it then does not increase the size of the machine while it is at a location which permits it to be readily removed.

In Fig. 14 a two color intaglio printing machine is shown constructed according to this invention, each unit of which is identical to the machine just described. These identical units are arranged in tandem so that the strip of material 63' may first be passed through one printing machine and then through the second to receive two colors. In other respects this form of the invention is similar to the previous form and similar parts may be recognized by the same reference numerals.

While I have illustrated and described the preferred embodiments of my invention, it is to be understood that I do not limit myself to the precise constructions herein disclosed and the right 55 is reserved to all changes and modifications coming within the scope of the invention as defined in the appended claims.

Having thus described my invention, what I claim as new, and desire to secure by United States Letters Patent is:—

1. In an intaglio printing machine a frame consisting of a base plate and a pair of spaced parallel vertical wall plates, an intaglio printing roller rotatively mounted between said wall plates, 65 and a doctor blade engaging said intaglio roller, said doctor blade comprising a rod, a blade substantially radially supported upon said rod and having its free end engaging said intaglio printing roller, head members on the ends of said rod 70 slidably engaging horizontal slots formed in said wall plates, resilient means urging said heads in one direction, and screws for holding the heads against the action of said resilient means.

2. In an intaglio printing machine a frame 75

consisting of a base plate and a pair of spaced parallel vertical wall plates, an intaglio printing roller rotatively mounted between said wall plates, and a doctor blade engaging said intaglio roller, said doctor blade comprising a rod, a blade substantially radially supported upon said rod and having its free end engaging said intaglio printing roller, head members on the ends of said rod slidably engaging horizontal slots formed in said wall plates, resilient means urging said heads in one direction, and screws for holding the heads against the action of said resilient means, said slots being provided with enlarged portions at specific areas through which the heads may be removed when the support rod is in a pre-determined position.

3. In an intaglio printing machine, a frame having a pair of spaced parallel vertical wall plates, formed with horizontal slots, an intaglio form roller rotatively mounted between said wall plates, and a doctor blade engaging said form

roller, said blade comprising a rod, a blade having one of its edges mounted on said rod and having its free edge engaging said form roller, cylindrical head elements on the ends of said rods formed with peripheral grooves which engage the material of the wall plates around said horizontal slots through which they engage for maintaining said rod in various slidable adjustable positions between said wall plates, a spring operating between one side of said head elements and the back end of said slot to urge said doctor blade away from said form roller, an adjustment screw threadedly engaged through said wall plate and extending into said slot and abutting the said head elements to hold said doctor blade in various adjusted positions with relation to said form roller against the action of said spring, and means for laterally oscillating said doctor blade in all the adjusted positions thereof.

JOSEPH BARASH. 20
